UNITED STATES PATENT OFFICE.

ALBERT H. STEBBINS, OF LOS ANGELES, CALIFORNIA.

CONCENTRATOR DECK.

Application filed June 3, 1927. Serial No. 196,366.

This invention relates to a novel form of concentrator deck having a material receiving valley in which separation of materials that differ in specific gravity is effected.

5 In carrying out the present invention the materials to be treated are advanced along a valley in the concentrator deck and a stratification of the materials is effected either through the use of air or by vibratory movement. The lighter materials are raised to the surface by the rising air currents, or by the heavier particles working down under them, and such lighter materials are disposed of by crowding them out of the valley. The 10 valley may be made as long as desired to give the heavier particles ample time to work down under the lighter particles.

One important feature of the present invention resides in scrapers arranged along the 15 valley and which serve to force the lighter materials or tailings laterally out of the valley while permitting the heavier particles or values to remain in the valley.

Another feature of the invention resides 20 in the construction whereby a concentrate confining pocket is formed near the discharge end of the valley and in which the materials are subjected to a panning action.

Another feature of the invention resides 25 in buffer blocks arranged at the sides of the valley to force the concentrates toward the centre of the valley and to crowd the tailings out of the valley.

Still another feature of the invention resides 30 in sides in a sloping portion of the deck and co-operating riffles for disposing of some of the tailings before the materials reach the treatment valley.

Other features of the invention and novel 35 combination of parts in addition to the above will be hereinafter described in connection with the accompanying drawings which illustrate one good practical form thereof.

In the drawings:—

40 Fig. 1 is a perspective view of a concentrator deck constructed in accordance with the present invention;

Fig. 2 is a top plain view of Fig. 1;

Fig. 3 on an enlarged scale is a perspective 45 view of portion of the deck of Fig. 1;

Fig. 4 is a vertical sectional view through portion of the deck valley;

Fig. 5 is a sectional view through the deck of Fig. 1 mounted upon a supporting frame;

50 Fig. 6 is a sectional view taken on the line 5--6 of Fig. 5;

Fig. 7 is a sectional view taken on the line 7—7 of Fig. 5;

Fig. 8 is a sectional view taken on the line 8—8 of Fig. 5;

Fig. 9 is a transverse sectional view through the deck valley showing the buffer blocks; and

Fig. 10 is a top plan view of the buffer blocks of Fig. 9.

The concentrator deck forming the subject 55 matter of the present invention is shown as mounted upon a supporting frame in approximately a horizontal position, and movement of the materials lengthwise of the deck is produced by imparting a progressive vibratory movement to the deck. This is not 60 essential, however, in all embodiments of the invention, for if desired the deck may be supported at a steep inclination in the direction of its length so that the materials being 65 treated will flow lengthwise of the deck under the influence of gravity.

In the construction shown the materials 70 to be treated are delivered to the concentrator deck by the feed hopper 10 having the sliding gate 11 which may be adjusted to control the rate of flow of the materials to the 75 deck surface from the feed hopper. That portion of the concentrator deck lying near the feed hopper 10 is preferably provided with 80 the oppositely inclined surfaces 12 which slope downwardly from the central ridge 13 that extends lengthwise of a portion of the deck as shown. The arrangement is such that 85 the opposite slope of the deck surfaces 12 will promote the flow of the materials down 90 these inclined surfaces towards the side walls 14 of the deck. Inclined riffles 15 provided upon that portion of the deck surface lying 95 near the feed hopper serve to direct the concentrates towards the material receiving valley, while the tailings or lighter materials 100 work laterally over the riffles down the inclined deck surface. As a result of the construction just described the materials undergo a preliminary treatment before they reach 105 the valley to be described, and in this manner the tailings which separate out promptly are prevented from reaching the valley.

In accordance with the present invention 110 the deck surface is provided with the treatment valley 16 which extends lengthwise of the deck a substantial distance, as shown, and the tailings which are crowded out of this valley, in a manner to be described, fall upon the launders 17, along which the tailings travel until they pass from the discharge

ends of the launders into the tailing receiving hoppers 18. The launders 17 preferably slope in the direction of their length with respect to the valley 16, as will be apparent from the drawing, so that the increased inclination of the surfaces 17 will promote travel of the tailings towards the hoppers 18. At each side of the valley 16 are provided the vertically disposed walls 19 and the upper edges of these walls lie flush with the side walls 20 of the valley, the arrangement being such that the materials which are crowded out of the valley 16 will readily work up the inclined walls 20 and fall upon the launders 17. The inclined wall 21 may be provided at the juncture of the ridge 13 and the valley 16 as shown. As above stated the concentrator deck shown is mounted upon a supporting frame to receive a progressive vibratory movement. This movement serves to work the concentrates down under the tailings and the stratification of the materials may be effected by movement alone, or if desired air passing upwardly through the materials may be employed to promote separation of the materials. In the present case the floor of the valley 16 is shown as having the air apertures 22 through which small jets of air may be delivered to the materials being treated. Air under pressure may be supplied to that portion of the deck surface lying near the feed hopper 10 and to the apertures 22 within the valley 16 by forming the air chamber or receptacle 23 below the deck surface, and since it is unnecessary to supply air under pressure to the launders 17 the air chamber 23 is preferably provided with a reduced portion 24 which lies under the valley 16.

The valley 16 is preferably so constructed that it decreases in width from its material receiving end towards its discharge end, as will be apparent from Fig. 2, this construction being desirable to crowd out of the valley the lighter materials as they approach the discharge end of the valley. Removal of the tailings or lighter materials from the valley is further promoted by providing any desired number of scrapers 25 which are conveniently arranged in diverging pairs, as best shown in Fig. 3. The lower portion of each scraper 25 lies in close proximity to the floor of the central portion of the valley while the lower edges of the outwardly flaring wings of the scrapers slope upwardly with respect to the inclined surfaces 20 of the valley, as best shown in Fig. 4. The arrangement is such that all materials traveling lengthwise of the valley will be deflected laterally by the scrapers but the concentrates lying beneath the tailings may work through the passages 26 provided between the lower edge of the scrapers and the deck surface, while the tailings will be deflected laterally by the scrapers out of the valley. It will therefore

be seen that the scrapers serve not only to deflect the tailings out of the valley, but also to deflect the concentrates laterally and up the side walls of the valley sufficiently to rework the concentrates and thereby retreat 70 or clean the same.

It may be desirable to increase or decrease the number of scrapers 25 employed, or to vary their position lengthwise of the valley, in accordance with the requirements of the 75 materials being treated. Means is therefore shown for supporting the scrapers in different positions of adjustment and consists of the posts 27 which are arranged in a row extending lengthwise of the valley, as shown, 80 and in order to give these posts the desired stiffness they may extend downwardly through the deck surface to the lower wall of the air chamber 24. The posts 27 are spaced apart sufficiently to receive between 85 them the intermediate portion 28 of a pair of connected scrapers 25 and the pair of scrapers may be secured to any post 27 in the desired position of adjustment lengthwise of the valley by a bolt 29. The outer end of 90 each scraper 25 is preferably provided with a downwardly extending leg 30 which may rest upon the surface 17. The legs 30 may be provided with the elongated slots 31 so that 95 they may be adjustably secured to the scrapers by the bolts 32. After the materials being treated have traveled a substantial distance along the valley 16 so that the concentrates have had an opportunity to work down under the tailings, it may be desirable to 100 crowd the concentrates inwardly towards the central portion of the valley. This may be done by providing the buffer blocks formed of the cooperating walls 33 and 34. The walls 33 are shorter than the walls 34 and 105 serve to direct the concentrates inwardly towards the central portion of the valley. These walls 33 extend upwardly from the inclined surfaces 20 a less distance than the walls 34 so that the tailings may flow over the 110 top of the walls 33 into spaces 35 (see Fig. 10), whereupon the materials that enter these spaces upon moving lengthwise of the deck will be directed out of the valleys by the higher walls 34. It will therefore be seen 115 that the buffer blocks just described perform the double function of crowding the concentrates inwardly towards the central portion of the valley and of working the tailings laterally out of the valley. The concentrates which have worked downwardly under the tailings within the valley 16 may be drawn off through any desired number of discharge openings 36, having the discharge pipes 37 120 that extend downwardly through the air chamber 24.

As the concentrates traveling along the valley 16 approach the discharge end thereof their movement lengthwise of the valley is arrested by the transversely extending wall 125

38 which wall is preferably given the stepped construction shown, to prevent the concentrates from working up this inclined wall. The tailings which still remain within the 5 valley when the concentrates reach the wall 38 will pass from the discharge end of the valley into the tailing receiving hopper 18^a, and as these tailings may differ somewhat from the tailings which enter the discharge 10 hoppers 18 it may be desirable to provide partitions between the hoppers 18 and 18^a, as shown. The tailings which work up the inclined wall 38 are prevented from escaping sidewise by the upstanding walls 39.

15 The transversely extending wall 38 serves to form a concentrate receiving pocket near the discharge end of the valley 16 and in which the concentrates may be subjected to a panning action under the vibratory movement imparted to the deck. This panning operation will serve further to work the concentrates down under the tailings, and as the concentrates accumulate in the pocket just mentioned they may be drawn off from 20 time to time through the discharge openings 36. In order to confine the concentrates within this pocket until they have undergone the desired panning operation, means should be provided for closing the lower end of the discharge pipe 37. This is conveniently done by 25 providing the bag or tube 40 shown in Fig. 5, and which may be twisted as shown to prevent the materials from passing therethrough, and the discharge end of this twisted tube may 30 be temporarily secured to the under surface of the deck as shown. Such fine particles as work through the air apertures 22 will fall upon the floor 41 of the air chamber, from 35 which they may escape through the discharge opening 42 into the tube or bag 40.

40 Various means might be provided for supporting the concentrator deck for reciprocatory movement in the direction of its length and the means shown in the drawings to this 45 end consists of the uprights 43 which are connected by the longitudinally extending rails 44, and the opposite sides of the supporting frame are connected by the transversely extending braces 45. The concentrator deck 50 may be rigidly secured to the carriage 46 and this carriage is mounted upon the supporting frame for movement in the direction of its length by the ball or roller bearings 47 which are confined between the bearings blocks 48 55 secured to the supporting frame and the bearing blocks 49 secured to the carriage 46. Air under pressure is supplied to the air chamber 23 by the fan 50 the discharge portion of which is connected by a flexible connection 60 51 to the downwardly extending portion 52 of the air chamber.

65 Various means might be provided for imparting a progressive vibratory movement to the concentrator deck and a simple means to this end is shown in Fig. 5 and consists of the

operating cable 53 an intermediate portion of which is secured to the carriage 46 by the clamping means 54. The portion of the cable 53 which extends in a right-hand direction from the clamp 54 extends around a grooved 70 idle sheave 55, and the lower end of this portion of the cable is secured to a coiled spring 56. The portion of the cable 53, which extends in a left-hand direction from the clamp 54 passes around a grooved idle sheave 57 and 75 passes from the lower portion of this sheave around a grooved sheave 58 which is mounted upon the eccentric 59, and the end of the portion of the cable extending from the sheave 58 is fastened to an anchor 60. The eccentric 59 is rigidly secured to a power shaft 61, the arrangement being such that rotation of the shaft 61 will rotate its eccentric to move the sheave 58 in an orbital path to thereby slack off and tension the cable 53. This will 80 serve to impart the desired progressive vibratory movement to the deck to advance the materials lengthwise of the same towards its discharge end.

85 While in most cases it may be desirable to impart a progressive vibratory movement to the concentrator deck forming the subject matter of the present invention this is not essential in all constructions, for if the deck is supported at a steep inclination in the direction of its length it will be unnecessary to vibrate the same since the force of gravity, together with the action of the air passing upwardly through the apertures 22, will produce the desired flow of the materials lengthwise of the deck. The air jets will serve also 90 to work the lighter materials upwardly through the concentrates to effect the desired classification, whereupon the tailings will be crowded out of the valley 16 by the construction above described.

95 From the foregoing description when read in connection with the drawings it will be seen that the materials undergo a preliminary treatment upon portions 12 of the deck surface before they reach the treatment valley 16, and that while traveling along this valley stratification is effected by the rising air currents and by the vibratory movement. The arrangement of the lower edges of the scrapers 25 so that the size of the passages 26 increase in an outward direction, together with the angular arrangement of these scrapers, prevents clogging of the materials within the passages 26, and the panning action to 100 which the concentrates are subjected near the discharge end of the valley serves to produce an exceptionally clean product.

105 What is claimed is:—

110 1. A concentrator deck, comprising in combination, a deck casing provided with a material supporting surface constructed and arranged to form a central valley extending lengthwise of the deck, means for directing the materials to be treated into the valley, 115 120 125 130

- scrapers mounted in the valley and constructed and arranged to direct the tailings up the inclined sides and out of the valley while permitting the concentrates to remain in the 5 valley, and said scrapers being mounted to lie in close proximity to the central floor of the valley to deflect all materials traveling along the valley laterally onto the inclined sides of the valley. 70
- 10 2. A concentrator deck, comprising in combination, a deck casing provided with a material supporting surface that is constructed and arranged to form a valley extending lengthwise of the deck, means for directing 75 the materials to be treated into the valley, and scrapers constructed and arranged to direct the tailings laterally out of the valley while permitting the concentrates to travel lengthwise of the valley under the scrapers, said 15 scrapers being also arranged to deflect the concentrates laterally within the valley to effect their retreatment. 80
- 15 3. A concentrator deck, comprising in combination, a deck casing provided with a material supporting surface that is constructed and arranged to form a valley extending lengthwise of the deck, means for directing the materials to be treated into the valley, and scrapers mounted in the valley to direct 85 the tailings out of the valley and having their lower edges inclined to the deck surface to provide outwardly flaring passages for the concentrates. 90
- 20 4. A concentrator deck, comprising in combination, a deck casing provided with a material supporting surface that is constructed and arranged to form a valley extending lengthwise of the deck, means for directing the materials to be treated into the valley to 95 travel lengthwise thereof, inclined scrapers arranged in pairs that flare outwardly from the bottom of the valley to direct the upper stratum of the materials up the inclined sides of the valley out of the valley and arranged so that the lower stratum may pass under the scrapers. 100
- 25 5. A concentrator deck, comprising in combination, a deck casing provided with a material supporting surface that is constructed and arranged to form a valley extending lengthwise of the deck, means for directing the materials to be treated into the valley to travel lengthwise thereof, a central wall mounted in said valley and extending lengthwise thereof, scrapers positioned in said valley and supported by said wall in spaced relation to the floor to direct the lighter materials out of the valley, and means for securing the scrapers to said wall in different 110 positions of adjustment lengthwise of the valley. 115
- 30 6. A concentrator deck, comprising in combination, a deck casing provided with a material supporting surface constructed and arranged to form a central valley extending 120 lengthwise of the deck, a series of scraper supporting posts mounted in said valley and arranged to form a wall extending lengthwise of the valley, scrapers for deflecting the lighter materials traveling along the valley laterally out of the same, and means for securing the scrapers to the different posts to vary their position lengthwise of the valley. 125
- 35 7. A concentrator deck, comprising in combination, a deck casing provided with a material supporting surface constructed and arranged to form a central valley extending lengthwise of the deck, a scraper supporting wall mounted in the valley to extend lengthwise thereof, a series of scrapers mounted in said valley and comprising deflector wings secured to said wall with their outer ends diverging therefrom in spaced relation to the floor of the valley and arranged to deflect the lighter materials laterally out of the valley while permitting the heavier materials to work under said wings, and downwardly extending legs at the outer ends of said wings and adapted to support the wings in spaced relation to the floor of the valley. 130
- 40 8. A concentrator deck, comprising in combination a deck casing having a central ridge near its material receiving end to extend lengthwise of a portion of the deck and having a material receiving valley extending lengthwise of the remaining portion of the deck, said ridge being provided with a deck surface that slopes downwardly from the opposite sides of the ridge, feed means for delivering the materials to be treated to the deck surface, inclined riffles upon the deck surface and arranged to direct the concentrates into said valley while the lighter materials flow over the riffles down the sloping deck surface, and means for crowding the lighter materials out of said valley. 135
- 45 9. A concentrator deck, comprising in combination, a deck casing having a central ridge near its material receiving end to extend lengthwise of a portion of the deck and having a material receiving valley extending lengthwise of the remaining portion of the deck, said ridge being provided with a deck surface that slopes downwardly from the opposite sides of the ridge, feed means for delivering the materials to be treated to the deck surface, inclined riffles upon the deck surface and arranged to direct the concentrates into said valley while the lighter materials flow over the riffles down the sloping deck surface, and scrapers constructed and arranged to direct the lighter materials out of the valley. 140
- 50 10. A concentrator deck, comprising in combination, a deck casing having a central ridge near its material receiving end to extend lengthwise of a portion of the deck and having a material receiving valley extending lengthwise of the remaining portion of the deck, said ridge being provided with a deck 145

- surface that slopes downwardly from the opposite sides of the ridge, feed means for delivering the materials to be treated to the deck surface, inclined riffles upon the deck 5 surface and arranged to direct the concentrates into said valley while the lighter materials flow over the riffles down the sloping deck surface, and said valley being provided with a cross-sectional area that decreases 10 toward its discharge end to crowd out of the valley the lighter materials.
11. A concentrator deck, comprising in combination, a deck casing provided with a material supporting surface constructed and arranged to form a valley extending lengthwise of the deck, means for directing the materials to be treated into the valley, means for crowding the lighter materials out of the valley, a concentrate retaining wall extending 15 across the valley near its discharge end to form a concentrate pocket, and means for removing the concentrates from said pocket.
12. A concentrator deck, comprising in combination, a deck casing provided with a material supporting surface constructed and arranged to form a valley extending lengthwise of the deck, means for directing the materials to be treated into the valley, means for crowding the lighter materials out of the valley, a concentrate retaining wall extending 20 across the valley near its discharge end to form a concentrate pocket, and means for vibrating the deck casing to subject the materials confined in said pocket to a panning action.
13. A concentrator deck, comprising in combination, a deck casing provided with a material supporting surface constructed and arranged to form a valley extending lengthwise of the deck, means for directing the materials to be treated into the valley, means for crowding the lighter materials out of the valley, and a series of steps arranged across 25 the valley near its discharge end to arrest the travel of the concentrates while permitting 45 the tailings to flow over the steps.
14. A concentrator deck, comprising in combination, a deck casing provided with a material supporting surface constructed and arranged to form a valley extending lengthwise of the deck, means for directing the materials to be treated into the valley, and buffer blocks arranged along the sides of the valley to crowd the concentrates toward the centre of the valley and adapted to direct the tailings 50 out of the valley.
15. A concentrator deck, comprising in combination, a deck casing provided with a material supporting surface constructed and arranged to form a valley extending lengthwise of the deck, means for delivering the materials to be treated into said valley, buffer blocks arranged along the sides of the valley to crowd the concentrates toward the centre 55 of the valley, and each buffer block having a low wall positioned to direct the concentrates inwardly but over which the tailings may escape.
16. A concentrator deck, comprising in combination, a deck casing provided with a material supporting surface constructed and arranged to form a valley extending lengthwise of the deck, means for delivering the materials to be treated into said valley, buffer blocks arranged along the sides of the valley 60 to crowd the concentrates toward the centre of the valley, and each buffer block having a low wall over which the tailings may escape while the concentrates are directed inwardly by such wall and also a high wall which extends away from the central portion of the valley.

In testimony whereof, I have signed my name to this specification.

ALBERT H. STEBBINS.
